15 Claims. (Cl. 179—8)

(Granted under the provisions of sec. 14, act of
March 2, 1927; 357 O. G. 5)

The present invention relates to a circuit arrangement for busy metering in automatic remote communication systems and more especially in automatic telephone systems.

In telephone systems of the automatic type wherein automatic switches are used for the purpose of setting up connections between various lines of the system, situations arise where all of the switches of a particular group or groups are busy at the same time so that a subscriber attempting to route a connection by way of one of the group of busy switches is precluded from completing the desired connection. In order to record this condition so that the operating engineers may be apprised thereof, it has been the practice in the past to provide, in association with a group of switches to be observed, a metering device which is operated when a call arrives and the all switch busy condition prevails, which device is held operated so long as the calling line, responsible for the operation of the metering device, is maintained in a calling condition. This arrangement is open to the objection that more than one overflow call cannot be handled at any one time, and hence only one of simultaneous or substantially simultaneous overflow calls is susceptible of being recorded.

The present invention overcomes this difficulty and permits of the registration of simultaneously or approximately simultaneously occurring calling impulses in that when all the lines of a group are busy and an impulse for taking a line of this group into use becomes operative switching means are transitorily operated to influence a busy metering device independently of the duration of this impulse.

Embodiments of the invention are shown in Figs. 1-6.

Fig. 1 shows a finder switch system including one means for metering calls when the finder switches are all busy.

Fig. 2 shows a modified form of the metering arrangement shown within the dotted lines in Fig. 1.

Fig. 3 is a further modification of said metering means.

Fig. 4 is also a modified form of the metering arrangement.

Fig. 5 comprises a further form of metering arrangement using a glow lamp.

For the purpose of clarity only those switching means are shown which are absolutely necessary to enable the invention to be understood.

The operations taking place in connection with

the arrangement according to Fig. 1 are as follows:

When subscriber T_n removes his receiver for the purpose of initiating a call the subscriber's loop is closed and the following circuit is set up: 5 earth, contact $1t$, subscriber's loop, contact $2t$, winding I of relay R, battery and earth. Relay R operates its contacts, connects up winding II of relay R and relay T to the lead passing to wiper c of the call finder AS by closing contacts $3r$ and $4r$ and at contact $7r$ establishes the following circuit for relay E for starting up the call finder AS: earth resistance W_{11} , contacts $6t$, $7r$, $15ab$ and $12p$, winding of relay E, battery and earth. 10 Relay E closes its contact $17e$ and thereby completes the following circuit for the stepping magnet D of the call finder AS: earth, battery, magnet D, contacts $17e$ and $18p$, relay interrupter UR and earth. Under the influence of the relay interrupter the stepping magnet D receives impulses 15 which promote the stepping of the wipers a, b, c of the call finder AS. When the call finder AS has reached the line leading to the calling subscriber T_n , i. e., when the wiper c has reached the contact over which the second winding of relay 20 R and relay T are connected the following testing circuit is established: earth, battery, winding of relay T, contact $4r$, (and parallel therewith $5t$) winding II of relay R, contact $3r$, wiper c of the call finder AS, windings I and II of 25 relay P, contact $10e$ and to earth in the following connecting device. In this circuit relays T and P energize while relay R is maintained energized. By closing contact $11p$, the high resistance winding II of relay P is short circuited 30 and the calling subscriber accordingly guarded against seizure on the part of another call finder. 35 By the opening of contact $18p$ the stepping circuit for the rotary magnet D is cut off and the call finder is thereby brought to rest. The switching through of the speaking leads to the following connecting device takes place at contacts $8p$ and $9p$. At contact $12p$ the circuit for relay E is broken so that contact $13e$ is closed and accordingly the start chain AN is switched 40 through to the relay E of another free call finder so that if a call is promoted by another subscriber the free call finder connected up over the start chain is started up. The energizing of relay T causes contact $5t$ to open. Relays T and R 45 are, however, as already described, maintained energized since relay R remains connected up over its winding II at contacts $3r$ and $4r$. By the opening of contacts $1t$ and $2t$, earth and battery and simultaneously winding I of relay R are 50 55

disconnected from the speaking leads. Finally by the opening of contact 6t the starting earth is disconnected over resistance W_{11} . After the switching through of the speaking leads at contacts 8p and 8p the following circuit is set up for relays A and B in the connecting device subsequent to the call finder AS: earth, battery, winding I of relay A, upper speaking lead, contact 8p, wiper a of the call finder AS, subscriber's 10 loop, call finder wiper b, contact 9p, winding I of relay B, and earth. The switching operations indicated by the energizing of relays A and B in the following connecting device are of no significance for the present invention so that a 15 detailed description will not be given. It will merely be mentioned that a calling signal AZ is connected to windings II of relays A and B over contacts which are not shown, which signal is induced in the windings I of these relays so that 20 it can be perceived by the calling subscriber. Only after this calling signal has been received does the subscriber establishing the call operate his dial switch for the purpose of transmitting impulse trains. The calling signal or "dial tone" 25 is disconnected after the first digit has been dialled (in a manner not shown). The setting up of the call takes place in the known way with which we are not further concerned.

It has already been mentioned that the starting 30 chain for the free call finders of a group is always switched on further to enable the establishment of calls over the call finders which are still free.

If it now so happens that all the call finders in a group are engaged it is not possible for the 35 calling subscriber to establish a call. It is of considerable importance for supervisory purposes to know how often this case arises so that from the data thus obtained variations can be made in the arrangement of the connecting devices 40 such as increasing the call finder groups or the like. For this purpose a metering device is provided which is operated each time a subscriber attempts to set up a call when all the call finders of a group are engaged. The criterion for all 45 the call finders of a group having been taken into use and there being no longer one available is constituted by the energizing of a relay AB. The operation of this relay can most simply be effected by extending the circuit for this relay through 50 the contacts controlled by the testing relays P of the individual call finders. If all the call finders of the group are engaged and thus all the P relays of these call finders are energized a circuit for relay AB is set up over the p-contacts of these 55 relays.

If under these conditions i. e., when relay AB is energized a subscriber takes up his receiver in order to set up a call the following circuit is closed over contact 7r by relay R (which is energized 60 in the manner described above); earth, resistance W_{11} , contacts 6t, 7r and 16ab, primary winding of the transformer T_7 , battery and earth. The impulse impressed in this manner on the primary side of the transformer is transmitted to the secondary winding and influences relay S associated with the secondary winding so that this relay is energized for a short time and then releases. As a result the contact 20s is opened, contact 19s is closed for a short time and contact 20s is again 65 closed. During the interval when the contact 19s is closed, the relay W is energized over the following circuit: earth, contact 19s, winding I of relay W, contact 22x, resistance W_{13} , battery and earth. Relay W closes its contacts 23w and 70 24w and opens its contact 26w. At contact 23w

a short-circuit is set up over winding II of relay W which has the effect of making this relay slow-to-release. When shortly afterwards contact 20s is again closed the following circuit is completed for relay X over contact 24w which is still closed: 5 earth, contacts 20s, and 24w, winding of relay X, battery and earth. Relay X opens its contact 22x which has no particular effect, and closes contact 25x. A short time later relay W falls back and at contact 24w breaks the circuit for relay 10 X. Relay X is a slow-to-release relay so that its contacts remain in the operated position for a short time. The metering device Z is now connected up over contact 26w in its normal position in the following circuit: earth, contacts 25x, 15 26w, and 27y, winding of meter Z, battery and earth. The meter is thus advanced one step forward. The operating time of the meter is determined by the release period of relay X, which shortly afterwards releases and opens the circuit for the meter once more at contact 25x. Subscriber T_n who is informed by the continuance of the dial tone that he cannot set up a call for the moment thereupon replaces his receiver. Relay R is accordingly deenergized and inter alia 20 opens contact 7r. The disconnecting impulse now operates on the primary of transformer T_7 , is transmitted to the secondary winding, and in a manner similar to that just described for the switching on impulse, produces a brief energizing 25 of relay S. The operations already described now take place for influencing meter Z. Thus when a call is initiated by a subscriber when all the call finders of a group are engaged the meter is advanced by two steps. Hence, it may be seen 30 that for determining the number of unsuccessful calls the position of the meter must be divided by two.

The case may occur in which the subscriber 35 who desires to set up a call operates his dial switch although the dial tone is not disconnected. Accordingly, relay R is caused to energize and release again a number of times. As a result, contact 7r is opened and closed a number of times and a number of connecting and disconnecting 40 impulses operate on the primary winding of the transformer.

If the subscriber after taking up his receiver 45 transmits, for example, one impulse without having received the dial tone contact 7r is opened and closed once. Accordingly, one connecting and one disconnecting impulse operates on the primary winding of the transformer T_7 . These two impulses are transmitted to the secondary winding and produce two brief operations of relay S. On the first operation of relay S and the consequent closing of contact 19s relay W is energized in the circuit described above. Because of the release of relay S and the closing of contact 20s which occur shortly after the energization of 50 relay W, the relay X is connected up as already described. Before relay W releases (its winding II is short-circuited by its own contact 23w), contact 19s is closed again. Accordingly, the following circuit is set up: earth, contact 19s, winding I of relay W, winding of relay Y released from the short-circuit by contact 22x, resistance W_{13} , battery and earth. Relay Y energizes in this circuit and establishes a locking circuit independently 55 of contact 19s: earth, resistance W_{12} , contact 21y, 60 winding of relay Y, resistance W_{13} , battery and earth. Relay S now falls back again, opens contact 19s and closes contact 20s. The circuit for relay W is thereby broken. The release of the individual relays takes place in the following way: 65

relay W first releases after the release period which is protracted on account of the short-circuiting winding II. Thereupon at contact 24w the circuit for relay X is broken. After a short 5 time this falls back and at contact 22x short-circuits the winding of relay Y. Only now after a definite time has elapsed does relay Y release.

If the circuit for the meter is considered it can be seen that no operation of the meter can be 10 produced by the transmission of impulses from the subscriber's station because before contact 26w is closed, that is before relay W has released, relay Y is energized and this at contact 27y disconnects the meter. Relay Y is the last of the 15 three relays to deenergize at the end of the numerical impulses, so that contact 27y is only closed when contact 25x is opened.

The case has been described in which the subscriber only transmits one impulse. Operation 20 of the meter is, however, prevented also when a number of impulses are transmitted since relay Y holds the circuit for the meter open until after the termination of the last impulse transmitted. As may be seen from Fig. 1 only a very short 25 time is necessary for registering an unsuccessful call, this time being determined by the release of relay W. Only if an attempt to set up a call by another station is made during this short time does the registration not take place, a disadvantage which can be tolerated since the 30 situation giving rise thereto only seldom occurs. If, however, relay W has released, another unsuccessful call will be registered independently of whether or not the subscriber Tn has replaced 35 his receiver.

Fig. 2 indicates another solution of the problem according to the invention and possesses the advantage over the arrangement shown in Fig. 1 that the devices effecting the registering of the 40 unsuccessful calls consist of normal relays in contradistinction to Fig. 1 where slow-to-operate relays have to be used.

The arrangement according to Fig. 2 is to replace that part of Fig. 1 which is enclosed by 45 dotted lines. The mode of operation of the arrangement according to Fig. 2 is as follows:

If when all the call finders are engaged the subscriber Tn takes up his receiver, the call receiving relay R is energized and closes contact r. 50 In the manner already described the relay S, connected to the secondary side of the transformer, is energized by induced impulses which are produced on the removal and replacement of the receiver by means of contact 7r. Thus on 55 the removal of the receiver at the subscriber's station contact 35s is closed for a short time and then opened again. At this point it should be noted that in comparison with the arrangement according to Fig. 1 the present network is 60 arranged so that relay S is only provided with the one operating contact 35s. This is an advantage insofar as contact 35s is easier to operate than is contact 19s in Fig. 1 which is constructed as a reciprocating contact for whose closing it is 65 necessary to overcome a definite tension.

When contact 35s is closed the following circuit is established for relay W: earth, contact 35s, windings I and II of relay W, contact 37x, battery and earth. In this circuit relay W operates, opens its contact 31w and closes contact 70 34w, (make-before-break contact). Relay X cannot operate since winding I of relay W has a very low resistance and practically constitutes a short-circuit for the higher resistance winding 75 of relay X. When contact 35s opens shortly

afterwards, relay X operates in the following circuit: earth, contact 34w, winding of relay X, winding II of relay W, contact 31x, battery and earth. Relay X closes contact 36x and thereby completes a short-circuit over winding II of relay W. At contact 36x the short-circuit over winding I of relay Y is removed. This relay cannot however energize since the relative resistances of the individual relays are so adjusted that when relay X is connected up first the relay Y 10 cannot energize. Contact 33x is closed and the meter Z is thereby transitorily connected up. At the end of the delayed period for the release of relay W, determined by the short-circuit of contact 36x, contact 31w is again closed before 15 contact 34w opens so that the following circuit is established for the meter Z: earth, contact 31w, 32y, and 33x, winding of meter Z, battery and earth. Shortly afterwards contact 34w opens the circuit for relay X. After the latter has 20 released the starting condition is once more set up. When the subscriber on realizing that he cannot establish a call for the moment replaces his receiver relay S energizes again and influences the meter once more as just described. 25 The setting of the meter must be divided by 2 in order to be able to determine the number of unsuccessful attempts to establish a call.

The device according to Fig. 2 prevents the metering arrangement being influenced by impulses which the subscriber may transmit although he does not receive dial tone. Should the subscriber thus transmit impulses relay S is operated a plurality of times in succession. On transmitting each impulse contact 35s is closed, 35 opened and then again closed and opened. When the contact 35s first closes W is caused to energize as above described. When the contact opens relay X is energized and at the same time relay W is maintained energized over winding II. By the 40 closing of contact 36x winding II of relay W is short-circuited and its release is thereby delayed for a short period. This delayed release, however, suffices to bridge over the impulse, i. e. the contact 35s is closed for the second time while 45 relay W still holds its contact 34w operated. The following circuit now obtains: earth, contact 35s, winding I of relay W, contact 36x, winding I of relay Y, battery and earth. Relay Y can now energize since the low resistance winding 50 I of relay W is already connected up. Relay Y operates its contacts i. e., it opens contact 32y thereby opening a point in the metering circuit and establishes the following locking circuit for itself at contact 38y: earth, contacts 39x, 38y, 55 winding II of relay Y, battery and earth. If the subscriber has transmitted a number of impulses the condition just described is maintained namely, the energizing of all the relays W, X, and Y, until after the last impulse contact 35s is opened 60 for a prolonged period. Relay W then releases. It opens its contact 34w and thereby breaks the circuit for relay X. The locking circuit for relay Y is only opened after relay X has released by the opening of contact 39x. Considering the circuit in which the meter Z is arranged it may be 65 seen that on transmitting impulses contacts 31w and 32y are opened and contact 33x is closed. After the release of the relay W the circuit for the meter cannot be established since contact 32y 70 is still open. Relay X now falls back, opens contact 33x and disconnects the meter. Only then does relay Y release. The closing of contact 32y has, however, no influence on the meter.

Fig. 3 represents an improvement in the devices 75

shown in Figs. 1 and 2 in that the short connecting and disconnecting impulses do not operate directly on the relay W but through the intermediary of an auxiliary relay H. Since the induced impulse is only of a very short duration it may happen that the brief closing of the operated contact of relay S does not have the desired effect, i. e., the energizing of relay W. Consequently, the operating contact of relay S indicated by the reference character 40s in Fig. 3 operates on a relay H which is quick-to-energize over the circuit: earth, contacts 40s, 41w, winding of relay H, battery and earth. The winding I of relay W is only connected up through the closing 10 of contact 43h whereupon the operations described above take place. Relay H remains energized in the circuit passing over contacts 42h and 41w until relay W has definitely energized. Relay H is then disconnected again by contact 41w.

Fig. 4 represents a further modification of the arrangements in Figs. 1 and 2, this figure replacing that portion of Fig. 1 enclosed by dotted lines. The arrangement according to Fig. 4 differs from that of Figs. 1 and 2 in particular in that the 15 relay S is not a normal relay as in Figs. 1 and 2 but is assumed to be a polarized relay having two windings of which one, which is not shown (winding I), is arranged in the secondary circuit of the transformer Tr. This arrangement enables a 20 single registration to be effected for the unsuccessful calls, so that the position of the meter indicates directly the number of these unsuccessful calls. Relay S on account of its construction as a polarized relay is only influenced by the 25 switching on impulse on the removal of the receiver at the calling station, but not by the disconnecting impulse taking place when the receiver is replaced.

The detailed operation of the arrangement according to Fig. 4 is as follows: When all of the 30 call finders of the group are engaged, the winding I (not shown) of the polarized relay S is influenced by the impulse induced in the transformer when the subscriber takes up the receiver. It accordingly opens its contact 47s and closes contact 46s, which remains closed for the moment. The 35 following circuit is accordingly set up: earth, contact 46s, winding of relay W, contact 45x, battery and earth. In this circuit relay W operates and by opening its contact 50w opens a point in the 40 metering circuit. It also closes its contact 38w and thereby energizes the opposing winding II of the polarized relay S in the following circuit: earth, contacts 46s and 48w, winding II of relay 45 S, battery and earth. Relay S disconnects itself in this way so that contact 47s again closes. Because of its slow-to-release characteristic, relay 50 W continues to hold its contacts in the operated position. The following circuit is set up for relay X: earth, contacts 47s, 49w, winding of relay X, battery and earth. Relay X opens its contact 45s, this being of no significance, and closes transiently the circuit for the meter Z at contact 52x. When relay W releases shortly thereafter the 55 circuit for the meter is completed as follows: earth, contacts 50w, 51y, and 52x, winding of meter Z, battery and earth. The meter accordingly takes one step forward. The circuit for the meter is 60 maintained until the end of the release period of relay X whose circuit was opened at contact 49w. The meter is then disconnected at contact 52x. On the replacement of the receiver at the calling 65 station no further influencing of the relay takes place since the polarized relay remains uninflu-

enced by the disconnecting impulse, which is in the opposite direction.

The arrangement illustrated in Fig. 4 also prevents the meter from being operated when the subscriber transmits numerical impulses when all the call finders are engaged. If, for example, two impulses are transmitted, a circuit is completed for relay W by the closing of contact 46x when the first impulse is transmitted, this taking place in the manner already described. Through the 10 closing of contact 48w the opposing winding II of the polarized relay S is connected up so that this relay is caused to release. Relay X is thereby caused to energize as described above. The slow-to-release characteristic of relay W is such that 15 the impulses are bridged over by this relay. Contact 46s is thus closed the second time before relay W has released. Relay S is again caused to release by means of its opposing winding II. When contact 46s closes for the second time the following 20 circuit is established for relay Y: earth, contact 46s, winding of relay W, winding of relay Y (whose short-circuit is removed by contact 45x), battery and earth. Relay Y locks up in the following 25 circuit: earth, resistance W15, contact 44y, winding of relay Y, battery and earth. At contact 51y the circuit for the meter is broken. Some time after the second opening of contact 46s relay 30 W falls back (it cannot remain energized over resistance W15 and earth) and opens contact 49w, thereby to break the circuit for relay X. Through the 35 closing of contact 45x a short-circuit is established over relay Y so that this circuit also releases. The circuit for the meter cannot be set up since relay Y remains energized and contact 51y remains opened until another point in the metering circuit is opened at contact 52x.

The arrangement according to Fig. 4 has one disadvantage and that is, if the subscriber transmits only one impulse a circuit is established for the meter which is therefore advanced one step since the polarized relay S is only once influenced on the transmission of one impulse and thus contact 46s is closed only once.

Fig. 5 represents an improvement in the secondary circuit of the transformer Tr, the improvement residing in the provision of a condenser Ko and a glow lamp G1 for separating the secondary winding of the transformer from the relay S. This arrangement is for the purpose of insuring a satisfactory operation of relay S. If, in the arrangement according to Fig. 1, the relay included in the secondary circuit of the transformer is made of low resistance to insure a ready response, the induced impulse must necessarily only attain a small maximum potential so that in certain circumstances the energizing of relay S is doubtful. If, however, the relay is made of high resistance and the peak potential is accordingly greater the relay energizes with more difficulty. In the arrangement according to Fig. 5 in which the secondary circuit is practically open the peak potential is very great and this insures the striking of the glow lamp and the energizing of relay S. As frequently mentioned in the foregoing description the arrangements according to Figs. 1-5 possess certain disadvantages in that the registration of unsuccessful calls is not always effected with certainty and that in special cases false registering can take place.

In Fig. 6 an arrangement is shown which obviates all these disadvantages and insures a satisfactory registration of all unsuccessful calls in all cases.

The mode of operation of the arrangement according to Fig. 6 is as follows. When the sub-

scriber T_n removes his receiver in order to set up a call the call receiving relay R energizes in the following circuit: earth, contact $55t$, subscriber's loop, contact $57t$, winding I of relay R , battery and earth. Relay R operates its contacts and at contact $58r$ connects the testing lead of the call finder to battery over winding II of relay R , contacts $60r$ and $61t$ and winding I of relay T . At the same time the following circuit is set up for relay E by the closing of contact $63r$: earth, contacts $62t$, $63r$, $65ab$ and $64p$, winding relay E , battery and earth. In this circuit relay E energizes, closes its contact $71e$ and thereby completes the following circuit for the rotary magnet D of the call finder: earth, battery, rotary magnet D , contacts $71e$, $78p$, relay interrupter UR and earth. The wipers of the call finder are stepped forward under the influence of the relay interrupter until they have reached the calling subscriber's line. The following circuit is then established: earth, battery, winding I of relay T , contacts $60r$ or $61t$, winding II of relay R , contact $58r$, wiper c of the call finder AS , windings I and II of relay P , contact $75e$ and to earth in the following connecting device. In this circuit relays P and T energize and the energizing of relay R is maintained. Relay P switches the speaking leads through at contacts $73p$ and $74p$, short circuits its high resistance winding II at contact $76p$, guards the calling line against being seized by a further call finder, brings the call finder to rest by opening contact $78p$, and at contact $64p$ breaks the circuit for relay E . Relay E releases and closes contact $61e$ so that the start chain An is switched through to the relay E of another free call finder. Relay T which likewise energizes as already mentioned opens its contacts $55t$ and $57t$ and thereby disconnects battery and earth and winding I of relay R from the speaking leads. Through contact $63t$ earth potential is disconnected from the start chain. The further establishment of the call and the setting of the subsequent connecting devices is of no interest in the present case.

Contact $65ab$ is closed if there are call finders available for setting up a call. When all the call finders of the group are engaged the relay Ab (not shown) is energized so that contact $66ab$ is closed. If under these conditions a subscriber, for example subscriber T_n , attempts to set up a call the call receiving relay R is switched on when he removes the receiver and by closing contact $63r$ sets up the following circuit: earth, contacts $62t$, $63r$, $66ab$, and $68g$, magnet D^1 of a meter switch ZW , which is here indicated by the metering switch and which operates after the manner of a call finder, battery and earth. In this circuit the rotary magnet D^1 of the meter switch energizes and advances the wipers one step. The rotary magnet D^1 possesses a contact $69d^1$ by the closing of which a circuit is established for the winding of relay G : earth, contact $69d^1$, winding of relay G , battery and earth. Through the opening of contact $68g$ the energizing circuit for the rotary magnet D^1 is opened and at contact $69g^1$ the circuit for relay D is broken again. The closing of contact $68g$ effects the further operation of the rotary magnet D^1 . The reciprocal play between the rotary magnet D^1 and the relay G continues until the wiper of the metering switch SW has reached the contact to which the calling subscriber is connected. The following testing circuit is then established: earth, battery, winding I of relay T , contact $60r$ or $61t$, winding II of relay R , contact $58r$, wiper

of the meter switch ZW , windings I and II of the testing relay P^1 , contacts $66ab$, $68r$, $62t$ and earth. In this circuit relay P^1 of the metering switch energizes and by closing contacts $70p^1$ short-circuits its high resistance winding. On account of the increase in current density thereby produced in the circuit set up above the relay T of the subscriber is also energized.

At the same time by the closing of contact $71p^1$ the following circuit is set up for the busy meter: earth, contact $71p^1$, winding of meter Z , battery and earth. The meter thus registers the unsuccessful attempt to set up a call. The testing relay P^1 of the meter switch ZW can only operate when the wiper of the meter switch reaches a contact to which a subscriber is connected who has taken up his receiver while relay Ab is energized. If the wiper of the meter switch ZW reaches a contact to which is connected a subscriber who has already set up a call over a call finder the relay P^1 of the meter switch ZW cannot energize since the testing relay P of the call finder is energized in series with the winding T^1 of relay T , and by closing its contact $76p$ has short-circuited its high resistance winding II. Because of the diversion of the current through the contacts $76p$ and the resulting low voltage drop across the low resistance winding P^1 , it is not possible for relay P^1 to energize in this case.

It has already been mentioned that if the wiper of the meter switch ZW passes on to a contact corresponding to a subscriber unsuccessfully attempting to set up a call a circuit is established in which in addition to relay P^1 of the meter switch, relay T at the subscriber's station is also energized. The subscriber's relay T energizes and locks its contacts. Because of the earth connection at contact $62t$ the circuit for the rotary magnet of the rotary switch ZW is disconnected so that the meter switch is brought to rest. At the same time relay P^1 of the meter switch is caused to deenergize and thereby disconnect the meter Z . At contact $62t$ the circuit for relays R and T is broken so that relay R which in contradistinction to relay T has no slow-to-release feature, falls back. Relay T , however, maintains its contacts in the operated position so that the following circuit is established: earth, contacts $58r$, and $54t$, subscriber's loop, contact $56t$, winding II of relay T , contact $59r$, winding I of relay T , battery and earth. This circuit is maintained until the calling subscriber replaces his receiver and thereby breaks the loop.

If now another subscriber attempts to set up a call the meter switch ZW is again started up by the closing of the contact corresponding to contact $63r$. Influencing of the meter Z cannot take place, however, when the meter switch reaches the first subscriber T_n since, due to the opening of contact $58r$ and $61t$, it is impossible for relay P^1 to energize when the contact to which this subscriber is connected is reached. The meter switch thus passes over this contact and steps until the second calling subscriber is reached and then effects the registering irrespective of the number of subscriber's who take up their receivers at the same time and attempt to set up a call all the subscribers are sought out in succession by the meter switch and a registration is effected for each one.

What is claimed is:

1. In a signalling system, a plurality of lines, a group of automatic switches adapted to be taken for use by calling ones of said lines and each operative to forward a connection from a

- calling line to a desired called line, registering means, means operative only when all of said switches are busy and responsive to an attempt of a calling one of said lines to take one of said 5 switches for use for causing said registering means to register the call, and means whereby said last-named means causes said register means to register two substantially simultaneous calls originated when all of said switches are busy.
- 10 2. In a signalling system, a plurality of lines, a group of call finders each having access to said lines, each of said finders, when assigned to the use of a calling line, being automatically operative to search for and seize the calling line, said finders being adapted to be assigned to successive calling lines in a definite order, registering means, means operative only when all of said finders are busy and responsive to the initiation of a call on one of said lines for causing said registering means to register the call, and means whereby said last-named means causes said registering means to register two substantially simultaneous calls originated when all of said finders are busy.
- 15 3. In a signalling system, a plurality of lines, a group of call finders having access to said lines, each of said finders, when assigned to the use of a calling line, being automatically operative to search for and seize the calling line, said finders being adapted to be assigned to successive calling lines in a definite order, a stepping switch having a plurality of positions each corresponding to one of said lines, means operative only when all of said finders are busy and responsive to the initiation of a call on one of said lines 20 for causing said stepping switch to operate to the one position corresponding to the calling line, registering means, and means responsive to the operation of said switch to said one position for causing said registering means to register the call.
- 25 4. In a signalling system, a plurality of lines, a group of call finders having access to said lines, each of said finders, when assigned to the use of a calling line, being automatically operative to search for and seize the calling line, said finders being adapted to be assigned to successive calling lines in a definite order, a stepping switch having a plurality of positions each corresponding to one of said lines, means operative only when all of said finders are busy and responsive to the initiation of a call on one of said lines 30 for causing said stepping switch to operate to the one position corresponding to the calling line, registering means, and means responsive to the operation of said switch to said one position for causing said registering means to register the call.
- 35 5. In a signalling system, a plurality of lines, a group of call finders having access to said lines, each of said finders, when assigned to the use of a calling line, being automatically operative to search for and seize the calling line, said finders being adapted to be assigned to successive calling lines in a definite order, a stepping switch having a plurality of positions each corresponding to one of said lines, means operative only when all of said finders are busy and responsive to the initiation of a call on one of said lines 40 for causing said stepping switch to operate to the one position corresponding to the calling line, registering means, and means responsive to the operation of said switch to said one position for causing said registering means to register the call.
- 45 6. In a signalling system, a plurality of lines, a group of call finders having access to said lines, each of said finders, when assigned to the use of a calling line, being automatically operative to search for and seize the calling line, said finders being adapted to be assigned to successive calling lines in a definite order, a stepping switch having a plurality of positions each corresponding to one of said lines, means operative only when all of said finders are busy and responsive to the initiation of a call on one of said lines 50 for causing said stepping switch to operate to the one position corresponding to the calling line, a testing circuit adapted to be completed when said switch is operated to said one position, a pair of relays included in said testing circuit, each of said relays being energized when said circuit is completed, registering means, means responsive to the energization of one of said relays for causing said registering means to register said call, means responsive to the energization of the other of said relays for interrupting said testing circuit independently of said switch, and means including said other relay for holding said testing circuit open until said call is abandoned.
- 55 7. In a signalling system, a plurality of lines, a group of automatic switches adapted to be seized by calling ones of said lines and each operative to forward a connection from a calling line to a desired called line, a relay operable between two positions, means operative only when all of said switches are busy and responsive to an attempted seizure of one of said switches by a calling line for causing said relay momentarily to operate from one of its two positions to the other, registering means, and means responsive to the operation of said relay to said other position for causing said registering means to register the operation of said relay.
- 60 8. In a signalling system, a plurality of lines, a group of call finders each having access to said lines, each of said finders, when assigned to the use of a calling line, being automatically operative to search for and seize the calling line, said finders being adapted to be assigned to successive calling lines in a definite order, a stepping switch having a plurality of positions each corresponding to one of said lines, means operative only when all of said finders are busy and responsive to the initiation of a call on one of said lines 65 for causing said stepping switch to operate to the one position corresponding to the calling line, a testing circuit adapted to be completed when said switch is operated to said one position, a relay operable between two positions, means operative only when all of said switches are busy and responsive to an attempted seizure of one of said switches by a calling line for causing said relay momentarily to operate from one of its two positions to the other, registering means, and means responsive to the operation of said relay to said other position for causing said registering means to register the operation of said relay.
- 70 9. In a signalling system, a plurality of lines, a group of call finders each having access to said lines, each of said finders, when assigned to the use of a calling line, being automatically operative to search for and seize the calling line, said finders being adapted to be assigned to successive calling lines in a definite order, a relay operable

between two positions, means operative only when all of said finders are busy and responsive to the initiation of a call on one of said lines for causing said relay momentarily to operate from one of its two positions to the other, registering means, and means responsive to the operation of said relay to said other position for causing said registering means to register said call.

10. In a signalling system, a plurality of lines, a group of call finders each having access to said lines, each of said finders, when assigned to the use of a calling line, being automatically operative to search for and seize the calling line, said finders being adapted to be assigned to successive calling lines in a definite order, a relay operable between two positions, means operative only when all of said finders are busy and responsive to the initiation of a call on one of said lines for causing said relay momentarily to operate from one of its two positions to the other, registering means, means responsive to the operation of said relay to said other position for causing said registering means to register said call, and means for preventing impulses transmitted over said calling line from falsely operating said registering means.

11. In a signalling system, a plurality of lines, a group of call finders each having access to said lines, each of said finders, when assigned to the use of a calling line, being automatically operative to search for and seize the calling line, said finders being adapted to be assigned to successive calling lines in a definite order, an impulse responsive relay, means operative only when all of said finders are busy and responsive to the initiation of a call on one of said lines for momentarily energizing said relay, a metering device including an operating winding, a circuit for energizing said winding, and a plurality of relays responsive to the operation of said impulse responsive relays for controlling the condition of said circuit, said plurality of relays being so connected and arranged that said operating circuit is completed once for each operation of said impulse responsive relay provided successive impulses causing operation of said impulse responsive relay are separated by more than a predetermined time interval and said operating winding is maintained interrupted if said impulses are separated by less than a predetermined time interval.

12. A metering network adapted to register current pulses transmitted thereto and comprising, in combination, an impulse responsive relay adapted to operate once during each pulse transmitted to said network, a metering device, means responsive to each operation of said relay for causing said metering device to register the corresponding pulse, and means for preventing said metering device from operating when the rate of said pulse is greater than a predetermined value.

13. A metering network adapted to register current pulses transmitted thereto and comprising, in combination, a pulse responsive relay, a metering device including an operating winding,

a circuit for energizing said winding, and a plurality of relays responsive to the operation of said pulse responsive relay for controlling the condition of said circuit, said relays being so connected and arranged that said operating circuit is completed once for each operation of said pulse responsive relay provided said pulses are separated by more than a predetermined time interval and said circuit is maintained interrupted provided said pulses are separated by less than 10 said predetermined time interval.

14. A metering network adapted to register current pulses transmitted thereto and comprising, in combination, a pulse responsive relay adapted to respond to pulses transmitted to said network, a metering device including an operating winding, a circuit for energizing said winding, a second relay operative in response to each operation of said pulse responsive relay only in the event said pulse responsive relay is not repeatedly operated at more than a predetermined rate of speed, said second relay, upon operating, being effective to open a point in said circuit, a third relay operative in response to the operation of said first relay, said third relay, upon operating, being effective to prepare said circuit, and said second and third relays being so constructed that said second relay restores before said third relay at the end of a received pulse, whereby said circuit is momentarily completed once for each operation of said pulse responsive relay.

15. A metering network adapted to register pulses transmitted thereto and comprising, in combination a pulse responsive relay adapted to respond to pulses transmitted to said network, a metering device including an operating winding, a circuit for energizing said winding, a second relay operative in response to each operation of said pulse responsive relay only in the event said pulse responsive relay is not repeatedly operated at more than a predetermined rate of speed, said second relay, upon operating, being effective to open a point in said circuit, a third relay operative in response to the operation of said first relay, said third relay, upon operating, being effective to prepare said circuit, said second and third relays being so constructed that said second relay restores before said third relay at the end of a received pulse, whereby said circuit is momentarily completed once for each operation of said pulse responsive relay, and a fourth relay controlled by said third relay and said pulse responsive relay, said fourth relay only being operative in response to the operation of said pulse responsive relay during an interval when said third relay is operated and being the last of said relays to restore following the restoration of said pulse responsive relay, and means controlled by said fourth relay for holding said circuit open so long as said fourth relay is operated.
